UNITED STATES PATENT OFFICE.

FRANK E. HULETT, OF CLEVELAND, OHIO, ASSIGNOR TO THE WELLMAN-SEAVER-MORGAN COMPANY, OF CLEVELAND, OHIO.

OPERATING MECHANISM FOR CLAM-SHELL BUCKETS.

No. 818,826.

Specification of Letters Patent.

Patented April 24, 1906.

Application filed August 25, 1904. Serial No. 222,170.

To all whom it may concern:

Be it known that I, FRANK E. HULETT, a resident of Cleveland, in the county of Cuyahoga and State of Ohio, have invented certain new and useful Improvements in Operating Mechanism for Clam-Shell Buckets; and I do hereby declare the following to be a full, clear, and exact description of the invention, such as will enable others skilled in the art to which it appertains to make and use the same.

My invention relates to an improved operating mechanism for clam-shell buckets, the object of the invention being to provide improved trolley construction and mounting whereby the operator's cab is carried by the trolley and the entire closing, elevating, and other movements of the bucket is entirely under the control of the operator in the trolley-cab.

A further object is to provide improved means for closing, elevating, and moving the bucket.

With these objects in view the invention consists in certain novel features of construction and combinations and arrangements of parts, as will be more fully hereinafter described, and pointed out in the claims.

In the accompanying drawings, Figure 1 is a view in elevation, illustrating my improvements. Fig. 2 is a side view of the trolley. Fig. 3 is a top plan view. Fig. 4 is an end view. Fig. 5 is a top view of the operator's cab, and Figs. 6 and 7 are diagrammatic views of the hoisting and holding cables and their drums.

This mechanism has been designed with a view of reducing the number of cables and parts necessary for operating buckets, (clam-shell;) also to enable the operator, who controls the various motions, to be located on the moving carriage, commonly called the "trolley," without the necessity of carrying the heavy hoisting machinery on this carriage. It is generally conceded that the operator should be located on this carriage, as it is a position from which he is better able to observe all the operations of the machine. It is considered quite a disadvantage, however, to put all the hoisting-motors on this carriage, as it involves increasing the weight of the carriage to such an extent that the entire weight and cost of the bridge or structure

carrying the trolley is greatly increased. This new arrangement also makes the hoisting and cross travel of the mechanism independent of each other, so that the bucket may be hoisted and the trolley traversed simultaneously. Another feature is the equalizing of the hoist-ropes at the bucket, so that if a bucket is tipped over sidewise or lengthwise the strain on the hoist-cable is always the same.

This mechanism is intended to be used on Gantry cranes and overhead conveyers, &c., which are most commonly used along the lakes for unloading coal, iron ore, limestone, sand, &c., from vessels, and also at blast-furnace plants for stocking and rehandling the material used in the manufacture of pig-iron.

1 represents a conveyer-bridge of any approved form, mounted at one end on the machinery-tower 2, which carries a motor or engine and a winding-drum, and at its opposite end the bridge is mounted on the tower 3, which towers move on suitable trackways. The bridge 1 and the boom or apron 4, which forms an extension of the bridge, are provided with a track 5, on which the trolley 6 travels, and a track 8 is also provided at any convenient point on the bridge for the travel of the sheave-carrier 7. In the present instance I have shown track 5 at the bottom of the bridge near its transverse center, and the track 8, on which the sheave-carrier 7 travels, is disposed in a plane above track 5; but these arrangements are not necessary and the location and positions of these tracks may be changed at pleasure.

From the hoisting-drum in the machinery-tower 2 runs the hoist line or cable 9, as clearly shown in Figs. 1 and 6. This cable 9 passes over sheaves 10 and around sheave 11 in sheave-carrier 7 and from thence back to a point 12 near the forward end of the bridge, where it is secured. Instead of securing the end of this hoist-cable to the point 12 the end of the cable or line may pass around a sheave at the point 12 and then back and secured to the sheave-carrier 7, as shown in Fig. 6, or the cable may be carried up over sheaves 10 and its ends secured to the sheave-carrier 7, as shown in dotted lines, thus dispensing with sheave 11 in said carrier.

The movements of the sheave-carrier 7 actuate a hoist-cable 13. One end of this

2

cable 13 is secured to the power-wheel of the automatic clam-shell bucket 15 and passes from thence over and preferably once or twice around sheave 16 in the trolley 6 and over a sheave 17 at the rear end of the bridge, thence forward around a sheave on the sheave-carrier 7, back around sheave 17^a on bridge, then forward over sheave 18 on the boom or apron 4 and rearward over sheave 19 on trolley 6, and down to the power-wheel of the clam-shell bucket 15. With this arrangement of cable the sheave on the carrier 7 engages a loop portion of the cable 13. Hence by moving the sheave-carrier forwardly the portion of the cable depending below the trolley 6 will be shortened and the bucket 15 elevated, while a reverse movement of the sheave-carrier lengthens such depending portions and lowers the bucket.

20 With the mechanism thus far described the bucket 15 can be lowered and hoisted. In addition to the hoisting - ropes above described the trolley 6 is provided with drums or sheaves 20, loosely mounted on the shafts 21, carrying the sheaves 16 and 19, over which the hoisting-cable passes, as before explained. Secured to these drums or sheaves are the holding - cables 22. These cables are connected at their lower ends to the bucket 15 25 for simply holding the same when the movable members or scoops of the bucket are released by the hoisting-cable. The sheaves or spools 20, to which the holding-cables 22 are secured and around which they wind, are connected to the sheaves or spools 16 and 19, 30 around which the hoisting-cable is wound, (a sufficient number of times to cause friction sufficient for imparting motion to the cable-holding spools,) by clutches (not shown) under the control of the operator, and the sheaves or spools 20, carrying the holding-cables 22, are provided with brakes 23 under the control of the operator in the cage or trolley.

35 In operation the bucket 15 is closed and hoisted on the hoisting-cables 13. As soon as it is closed, however, before hoisting it is necessary to start the machinery in motion, which hoists up the hold-ropes 22 to prevent 40 accumulation of slack in these ropes. When the bucket is hoisted and conveyed and ready to dump, it is necessary to set brakes 23 on the spools or drums carrying the hold-cables 22 and slack off on the hoist-cables. This 45 throws the weight of the bucket on the hold-ropes and the bucket opens by gravity. In this arrangement the hold-cables 22 are wound in and unwound from spools 20, running loose on the same shafts as the hoist-spoils 16 and 19 on the trolley. They are actuated by a 50 suitable clutch thrown by the operator. This clutch connects the hold-rope spools and hoist-rope spools together, and they turn in the same direction with the same speed, due to the friction of the hoist-cables around the

55 hoist-spoils. Located on the trolley 6 and connected by gear-wheels 24, 25, 26, and 27 with one set of track-wheels of the trolley is a motor 28 for imparting travel to the trolley, suitable brakes 29 being provided, as shown, for stopping and locking the trolley at any point of its travel. The trolley is provided with a cage 30 for the operator, and this cage has installed therein the necessary controller for the motor and the levers for actuating the clutches on the hold sheaves or spools and the necessary levers for the brakes of the track - wheels and hold sheaves or spools. As the operator in the cage controls all the movements of the trolley, it is of course essential that the motor in the tower 2 which actuated the hoist-cable 13 be also under his control, and this can be accomplished by trolley-wires running through the bridge and electric pick-ups attached to the carriage and connected to a controller located in the operator's cage on the trolley.

60 A great many slight changes might be made in the general form and arrangement of the parts described without departing from my invention, and hence I would have it understood that I do not restrict myself to the precise detail set forth, but consider myself at liberty to make such slight changes and alterations as fairly fall within the spirit and scope of my invention.

65 Having fully described my invention, what I claim as new, and desire to secure by Letters Patent, is—

1. In an operating mechanism for clam-shell buckets, the combination with a bridge, a track thereon and a trolley mounted to run on said track, of an operator's cage on said trolley, an electric motor in the cage adapted to propel the trolley on the track, hoisting and holding drums or spools on the trolley, cables on said drums or spools, pulleys at the ends of the bridge over which the cables are passed, an auxiliary carriage on the bridge, sheaves thereon over which the hoisting-cable passes between its ends, means for moving said auxiliary carriage, and a clam - shell bucket secured on the ends of said cables.

70 2. In a hoisting and conveying apparatus, the combination with a bridge, of a bucket, a trolley, an operator's cage on the trolley, a hoist-cable connected at its ends to the closing mechanism of the bucket and passing in opposite directions around and over sheaves in the trolley and around sheaves on the bridge, a second hoist-cable carrying a sheave engaging a looped section of the first-mentioned hoist-cable, a drum for actuating the second hoist-cable a motor in the operator's cage and gearing connecting said motor and the track-wheels of the trolley.

75 3. In a hoisting and conveying apparatus, the combination with a bridge of a bucket, a trolley, an operator's cage on the trolley, a hoist-cable connected at its ends to the clos-

ing mechanism of the bucket and passing around and over drums or sheaves on the trolley and around sheaves on the bridge, a second cable carrying a sheave engaging a 5 looped section of said first-mentioned hoist-cable, a drum for actuating the second hoist-cable, a pair of holding drums or spools actuated by the movements of the hoisting drums or spools, cables connected to said holding- drums and also to the bucket and brakes for 10 said holding-drums.

In testimony whereof I have signed this specification in the presence of two subscribing witnesses.

FRANK E. HULETT.
